(57) **CLAIM**

The ornamental design for a disk shaped pole mounted LED light fixture, as shown and described.

DESCRIPTION

FIG. 1 is a bottom perspective view of the new design; FIG. 2 is a top perspective view thereof; FIG. 3 is a top view thereof; FIG. 4 is a bottom view thereof; FIG. 5 is a front side view thereof; FIG. 6 is a left side view thereof; FIG. 7 is a rear side view thereof; and, FIG. 8 is a cross-sectional view of a top portion thereof taken along line 8-8 of FIG. 3.

The design consists of the features of shape, ornament and configuration of the article shown in the drawings. The broken lines shown in the drawings are for the purposes of illustrating portions of the article that form no part of the claimed design. The right side view is a mirror image of the left side view and is therefore omitted. The cross-sectional view is included to further illustrate certain interior portions of the embodiment visible through openings in the outer surface.
